UNITED STATES PATENT OFFICE

DAVID C. WILLIAMS, OF MEDFIELD, MASSACHUSETTS, ASSIGNOR TO HENRY F. HURLBURT, JR., OF WELLESLEY, MASSACHUSETTS

PACKING FOR SAFETY-RAZOR BLADES

Application filed June 13, 1928. Serial No. 285,041.

My present invention has for its object a new and improved packing for holding safety razor blades in position for shipment and use and an improved method of withdrawing blades from the package one by one as needed. Heretofore it has been customary to wrap each razor blade in a piece of parchment or oiled paper which is folded about the blade or to place each blade in a wrapper which is essentially a small envelope. Thereafter the wrappers containing the individual blades are placed within small cartons holding a given number, usually 5, in which they are sold to the customer. To use the blades it is necessary to remove one blade and its wrapping from the carton, then open the envelope or wrapping and take out the blade. This requires considerable manipulation and occupies an appreciable amount of time frequently at a time when the user is in a hurry. There is also danger of cutting the fingers in removing the blade from its wrapping. The so-called magazine type of razor is one attempt to overcome the objections.

My present invention has for its object a new and improved form of wrapping, packing and withdrawing each blade from the carton which makes one blade instantly available without undoing any wrapping or envelope and without removing other blades from the carton. When in place in the package, the blades are held securely against injury particularly anything coming in contact with the edges of the blades. Furthermore there is no danger that the user will cut his fingers in removing the blades from the package, and danger of anything touching the edge of the blade is reduced to a minimum.

The invention will be fully understood from the following description when taken in connection with the accompanying drawings and the novel features thereof will be pointed out and clearly defined in the claims at the close of this specification.

Referring to the drawings,

Fig. 1 is a plan view of a packing embodying my invention the first blade having been withdrawn.

Fig. 2 is a side elevation of the packing shown in Fig. 1.

Fig. 3 shows the first blade and its part of the packing severed from the rest of the packing.

Fig. 4 is a longitudinal section of a package containing five blades.

Fig. 5 is a view on a smaller scale of the whole packing strip for five blades.

Fig. 6 is a view in perspective showing the end of the packing.

Referring to Fig. 1 the packing comprises essentially a carton 11 and a packing strip 12. The carton 11 is provided with a curved slot at one end (Fig. 6) and the other end is closed or sealed. The packing strip 12 (see Fig. 5) comprises alternate blade-receiving sections 13, 14, 15, 16 and 17 and tab sections 18, 19, 20, 21 and 22. There is also a tab 26 formed at the leading end of the strip formed from one half of a tab section. The tab sections are preferably narrowed in the middle and may be perforated, creased or otherwise weakened between their ends so that they can be easily severed at this point. There is a distinct advantage in reducing the width of the tabs 18 and 19 so that the ends of the adjacent tabs converge toward the weakened line 28. By so reducing the width of the tabs it is a simple matter for the user to sever the tabs to remove a blade and its supporting section and attached tabs from the strip remaining in the container, whereas if the tabs were all the same width as the blade receiving and supporting sections 13, etc., it would be more difficult to separate them, taking into consideration the fact that often the user's hands are wet or soapy and it is desirable to reduce the effort necessary to sever the tabs as much as possible.

The 90 packing strip 12 is made of any suitable paper preferably a thin tough paper such as a thin kraft paper and there is one blade-receiving section for each of the blades to be contained in the package. Each blade-receiving section is slightly wider than the blade to be packed so that the edge of the paper will project slightly beyond the edge of the blade or both edges, if it is a double edge blade and protect the blade from contact with the 100

walls of the carton. This is clearly seen in Figs. 1 and 3 where the blade is designated 23. For use in my improved packing each blade is provided with one or more holes 24 to receive ears 25 which are cut out and struck up from the blade-receiving section of the packing strip being located in such a position as to pass through the holes in the blade and fold over the adjacent part 10 of the blades and thus position the blade properly with relation to the edges of the packing strip. Very little strength is required to hold the blades in place since it is only necessary that the ears 25 prevent side- 15 wise movement of the blade in the package. While the principal function of the ears is to hold the blade in place against movement laterally, nevertheless it will be understood that they also assist in removing the blade 20 when a tab is pulled outwardly from the container. The ears readily accomplish this as when the blades and blade-receiving sections of the packing strip are folded and thereby superposed upon each other the blade cannot 25 escape from the strip without cutting the ears. This holds the blades securely in place and prevents any movement of the blade in the carton. Each tab is numbered to indicate the number of blades withdrawn from 30 the package, and to also apprise the user of the exact number of blades remaining in the package. This is important since the package is normally a closed one. In use, the blades are drawn out through the slot in the 35 container and it is not intended, nor is it necessary, to open the package.

The several blades are superposed in their proper position upon the blade-receiving sections of the packing strip and are formed into a bundle as shown in Fig. 4 by folding the tab sections of the packing strip upon each other between the blade-receiving sections. The tab 26 on the leading end of the strip is allowed to project slightly from the 45 package and is then folded over the end of the package so that it is in position to be seized by the user.

After opening the package the user seizes the tab 26 and pulling out the first part of 50 the packing strip and with it the first blade, the blade being held in place partly by the small ears 25, 25 and partly if so designed because its rear edge rests against the fold 27 in the packing strip. The user then severs 55 the packing strip along the weakened line 28 thus forming a new tab *c* (this being the one numbered 2 on the packing strip) in position to be seized to enable the user to withdraw the second blade when required. 60 It will be seen that there is always a protruding tab in position to be seized by the user to withdraw the next blade and that the tab shows the number of blades withdrawn from the packing.

65 I find in practice that the packing makes

it possible to withdraw the blades almost instantly from the package and to eliminate the waste of time heretofore required. There is also no necessity for taking the bundle of blades out and then returning to the carton 70 all except the one which is used. It is practically impossible for the user to cut his fingers in withdrawing the blades and the blades not in use are fully protected. The expense of packing is also materially reduced. 75

What I claim is

1. A packing for safety razor blades, comprising a strip of paper folded transversely of its length to form alternate blade receiving sections and tab sections of equal length, 80 said tab sections being of reduced width to facilitate detaching a blade and its receiving section from the remainder of the strip and certain of said tabs being numbered consecutively whereby the user is apprised of the 85 number of blades remaining in the packing, 90 blades carried by said strip and supported by said blade receiving sections longitudinally of said strip with the edges thereof adjacent the edges of the strip, said blade receiving section having a width in excess of the width of the blade to protect the edges thereof and the hands of the user after removal from the remainder of the strip and a length substantially equal to the length of the blade, and 95 means for detachably securing a blade to said 100 blade receiving section.

2. A package for safety razor blades, comprising a closed container having a slot in one end thereof, a strip of paper folded transversely of its length to form alternate blade receiving sections and tab sections of equal length positioned within the container, said tab sections being of reduced width to facilitate detaching a blade and its receiving and supporting section from the strip remaining in the container and certain of said tabs being numbered consecutively whereby the user is apprised of the number of blades remaining in the package, blades carried by said 105 strips and supported by said blade receiving sections longitudinally of said strip with the edges thereof adjacent the edges of the strip, said blade receiving section having a width in excess of the width of the blade to protect the edges thereof and the hands of the user after removal from the remainder of the strip and a length substantially equal to the length of the blade, means for detachably 110 securing a blade to said blade receiving sections, and a tab protruding through said slot to facilitate withdrawal of said strip and supported blades as desired. 115

In testimony whereof I affix my signature.

DAVID C. WILLIAMS. 125
